UNITED STATES PATENT OFFICE.

FRANK C. HEINEN, OF CHICAGO, ILLINOIS.

MAGNETIC SEPARATOR.

1,026,673.

Specification of Letters Patent.

Patented May 21, 1912.

Application filed August 10, 1908. Serial No. 447,675.

To all whom it may concern:

Be it known that I, FRANK C. HEINEN, a resident of Chicago, in the county of Cook and State of Illinois, have invented certain new and useful Improvements in Magnetic Separators, of which the following is a full, clear, and exact description.

The invention relates to magnetic separators, and more particularly to that type 10 in which a cylinder or drum is employed for displacing the magnetic, from the non-magnetic, particles.

In magnetic separators in which a cylinder or drum serves as the carrier for the 15 magnetic particles, the capacity and efficiency of the separator are limited by the number of electro-magnets which may be disposed in the carrying-arc or range of action. The capacity and efficiency of cylindrical separators are further limited by reason 20 of the fact that the axes or lines of magnetic force are across or between the edge-portions of the pole-pieces leaving the central portion of the face of the pole-piece in- 25 effective to attract and hold small magnetic particles or substances particularly those of low magnetic susceptibility. In magnetic separators in which the material is carried over a stationary or flat pole-piece it has 30 been proposed to increase the efficiency and capacity of the machine by dividing the pole into a series of magnetically separated face- 35 portions, so that magnetic lines of force emanate from the edges of the magnetic face- portions to render a greater portion of the face efficient and active in attracting magnetic particles. However, in said machines in which stationary pole-pieces are em- 40 ployed, a belt or carrier is necessary to convey the material into and out of the field of the magnet, and resultantly the efficiency of the separator particularly with respect to 45 particles of low magnetic susceptibility, was decreased by the interposed carrying-belt or body.

One of the important objects of the invention is to provide a separator in which a rotatable cylinder or drum on which the pole-pieces are mounted, constitutes the carrier 50 for the material and in which each peripheral pole-piece has its operative face divided by non-magnetic or dia-magnetic strips or bodies into a series of separated polar face-portions, from each of which magnetic lines of force emanate, to render a greater portion of each polar face active

and efficient in attracting magnetic particles; resultantly, the material may be brought directly into contact with the magnetized face-portions of the pole-pieces 60 without the interposition of a carrier, and by dividing the face of each pole-piece into separated face-portions, edge-portions of the face-portions in large number are provided throughout the entire area of the face- 65 portions, excepting those formed by the non-magnetic or dia-magnetic bodies, which are efficient in attracting and separating particles from the ore or gangue. Thus, both the efficiency and separating capacity 70 of the machine are increased by providing pole-pieces having their operative or magnetic faces formed to constitute a peripheral section of the cylinder or drum and dividing each face into a large number of cylindrical 75 polar face-portions.

The invention further designs to provide a structure in which the interior periphery or bore of the rotatable cylinder is constituted of pole-pieces, having their faces 80 divided into separate face-portions to adapt the separator for the separation of magnetic particles from wet material or that in which the solids are carried in suspension in water and is caused to travel longitudinally 85 through the cylinder rather than around the cylinder.

The invention further designs to provide a magnetic separator of improved construction in which the interior periphery of the cylinder or drum is constructed so that it is water-tight and adapted for use in separating magnetic particles from wet deposits. 90

The invention consists in the several novel features hereinafter set forth and more particularly defined by claim at the conclusion 95 hereof.

In the drawings: Figure 1 is a longitudinal section of a separator embodying the invention. Fig. 2 is a front end elevation. Fig. 3 is a section on line 3-3 of Fig. 1. 100

In the preferred form of the invention exemplified in the drawings, the separator comprises a rotatable cylinder, usually mounted at an inclined angle to cause the 105 material to flow therethrough by gravitation, and having an interior periphery or bore through which the material to be separated passes, and into which it is fed at one end. The cylinder is revolvably mounted on 110 a suitable frame 12. Rollers 16, mounted on shafts 15 serve to revolvably sustain the

drum or cylinder, said shafts being mounted in suitable brackets or bearings 14 on the frame 12. The drum or cylinder is provided with bands 11 which travel on said 5 rollers 16. The drum is secured against longitudinal movement by a bracket 23 in which are journaled suitable thrust-rollers 24. Any suitable mechanism may be provided for rotating the drum, that illustrated 10 comprising a sprocket-wheel 18, on each of the roller-shafts 15, a chain 17, and a sprocket-wheel 19 mounted on a drive-shaft 20.

15 The rotatable cylinder comprises an external para-magnetic shell 27 and an internal periphery over and through which the material to be separated, is adapted to pass. This internal periphery is formed by a series of arcuate heads 30 which are 20 integrally formed with magnet-cores 29 extending between the heads and the exterior shell and secured to the latter by screws or bolts 29'. The inner polar face of each arcuate head forms a curved section of the 25 internal operative periphery of the cylinder so that all of the faces of the pole-pieces will be concentric when assembled and in operative relation. The sides 33 of the pole-heads are outwardly tapering to provide a 30 correspondingly tapered space for a non-magnetic wedge strip 31, the inner face of this wedge-strip forming the internal peripheral portion between the polar faces and each wedge-strip is secured to the exterior 35 shell by a bolt 32 and magnetically separates the adjacent pole-pieces from each other. Each pole-piece extends from end to end of the cylinder so the material will be magnetically influenced from the time it passes 40 into the cylinder until it passes out of it. Suitable coils 36 are wound on the cores 29 of each pole-piece.

45 Since the cylinder is particularly adapted for separating wet deposits, it is necessary to make the internal periphery water-tight to prevent leakage into and around the coils. For this purpose, packing-strips 31' are 50 interposed between the wedge-strips 31 and the sides of the pole-heads, so that as bolts 32 are tightened, strips 31 will be wedged tightly between the adjacent pole-heads and an effective water-tight connection between the parts is effected, so that the interior periphery of the cylinder will be water-tight 55 throughout. The pole-pieces thus constitute sections of the internal periphery and the adjacent coils are suitably wound to induce a magnetic flow, as indicated by arrows in Fig. 3, so that the polar faces of each section or head will be of the opposite sign or polarity, thus producing a magnetic field between the polar faces of the adjacent sections. Each inner face of the pole-piece is constituted of a plurality of narrow longitudinally extending face-portions which

are separated from one another and the spaces between the face-portions are filled with non-magnetic material, such as brass or Babbitt metal, to magnetically separate the separated face-portions of each polar 70 face.

In practice it has been found that when the polar face is not divided, the edges of the polar faces have greater attractive powers than the central portions thereof and by dividing the operative face of each pole-piece into a plurality of small or narrow separated face-portions and dividing them by non-magnetic fillings, the entire face of the pole-piece is rendered effective so that 80 the capacity and efficiency of each pole-piece will be increased. A pole-piece embodying these characteristics is formed by providing the head with a number of longitudinally extending laterally narrow para-magnetic 85 strips 34 which are secured in grooves in the head and filling the spaces between the strips with Babbitt metal or brass, preferably the former.

85 In constructing the cylinder, the sections or pole-pieces are secured to the outer shell and the division-strips are secured in place and then by boring the internal periphery all portions thereof formed by the polar face-portions, the fillings and the division-strips will be rendered concentric to form a smooth and water-tight surface over which wet material will readily flow. Furthermore, by extending the pole-pieces longitudinally throughout the length of the internal periphery of the cylinder and providing the pole-pieces with a series of magnetically separated face-portions, wet material as it passes through the cylinder is subjected to the magnetic forces during a long 100 period, resulting in the separation of particles of low magnetic susceptibility.

At the upper end of the cylinder, a plate 40 of insulating material is secured and a contact-ring 41 to which one end of the 110 windings for each pole-piece is connected, is secured on said plate. The opposite end of each winding is connected to a contact-arm 42, a series of such being mounted upon the plate 40, and each arm carries a brush 43. Upon the frame 12 is mounted a pair of standards 44 carrying an insulating ring 45 having thereon a stationary segmental contact 45' which is arranged to contact with such brushes 43 as may be passing in 120 the corresponding arc of their rotation. A brush 46 has a constant bearing upon contact-ring 41. The segment 45' is usually semi-circular or approximately so, and extends from a point on one side of a vertical 125 plane to a point upon the opposite side of such vertical plane near the top of the cylinder. Consequently when rotation is imparted to the cylinder in the direction of the arrow (Fig. 2) each winding will be 130

energized during the time that it is passing through the bottom of its cycle of rotation until it reaches a point near the top of the machine when brush 43 passes out of contact with contact 46 and the coil becomes successively deenergized. To minimize the arcing on the separation of the brushes, I arrange a magnet blow-out 47 at the end of arcuate contact 45 as shown in Fig. 2.

10 To each end of the cylinder is secured a cylindrical extension indicated respectively at 48 and 49, each affording an extension of the interior periphery of the cylinder. Extension 48 is arranged to receive the 15 gangue from a feed-spout 40 which receives it from any suitable source of supply and the extension 49 forms a discharge or education spout for delivering the residual material from which the magnetic material 20 has been separated by the machine.

Within the cylinder and its extension, a tray or pan 51 extends in parallelism and is in proximity to the upper portion of inner periphery of the cylinder, such tray being 25 mounted upon suitable supports 52, 53, and open at its tail end to deliver the separated material where desired. A spray-pipe 55 extends longitudinally of the cylinder and is arranged to wash the internal periphery 30 thereof downwardly against the direction of rotation of the cylinder and similar spray-pipe 56 is arranged between the pan 51 and the top of the cylinder to wash the surface of the cylinder above the pan and said 35 spray-pipe also directs the spray in direction opposite to the rotation motion of the cylinder. A scraper 60 is also secured to the spray-pipe 56.

In operation, current being supplied, the 40 pole-pieces will be successively energized through a portion of each revolution from the time they reach the bottom until the inner pole-faces reach the upper portion of their path. Resultantly the strongly 45 magnetized face-portions of each pole-piece will contact with the magnetic particles in the mass of material fed into the head-end of the machine and traversing the cylinder longitudinally during its rotation. In passing 50 through the cylinder, the material will be agitated so that all particles thereof will, at some time, be brought within the magnetic field. The para-magnetic particles attracted by the para-magnetic face-portions 55 of each pole-piece will be lifted thereby until they are discharged into the pan 51. Spray-pipe 55 will wash back the dia-magnetic particles so that they will not be carried upwardly into the pan 51. Successive 60 deenergization of the polar faces occurs as they pass over the pan or tray 51 and in event there is residual magnetism in the pole-faces, spray-pipe 56 and scraper 60 will cause the particles to be delivered into the 65 tray.

The invention thus provides a separating cylinder having an extended internal periphery over which the material to be separated is passed and by which it is agitated in transit through the cylinder to insure 70 the bringing of all para-magnetic particles whether of high or low magnetic susceptibility into the magnetic field.

The longitudinally extending narrow and magnetically separated face-portions of each 75 pole-piece, increase the capacity and efficiency of the structure. The structure provides one in which the polar faces are constituted of a plurality of magnetically separated face-portions embodied in the internal 80 operative periphery of the cylinder and adapted for the separation of magnetic particles from wet gangue or material. The internal periphery, being formed of sections and water-tight connections therebetween, 85 adapts the structure for the treatment of wet material and avoids all danger of the passage of water to the coils.

The invention is not to be understood as restricted to the details set forth since these 90 may be modified within the scope of the appended claims without departing from the spirit and scope of the invention.

Having thus described the invention, what I claim as new and desire to secure by Letters Patent, is:

1. In a magnetic separator, a rotatable cylinder comprising a plurality of sections each having an arcuate polar face forming a section of the operative interior periphery 100 of the cylinder, means for magnetizing said sections, means for feeding the material to be separated to said cylinder, and removable non-magnetic division strips between and locking said sections against inward radial movement and having faces concentric with said polar face-portions.

2. In a magnetic separator, a rotatable cylinder comprising a plurality of separately removable sections each having an arcuate 110 polar face forming a section of the operative interior periphery of the cylinder and tapered on its sides to enlarge outwardly, removable non-magnetic filling strips having similarly tapered sides interposed between 115 the tapered sides of said face-portions to lock the same against inward radial movement, and having their faces substantially concentric with said arcuate polar face-portions, means for magnetizing said sections, 120 and means for feeding the material to be separated into the cylinder.

3. In a magnetic separator, a rotatable cylinder comprising an exterior para-magnetic shell, pole-pieces having radially extending cores and arcuate heads having inner polar faces forming a section of the internal periphery of the cylinder and formed to leave tapered spaces between the contiguous edges of the adjacent heads, non-magnetic 130

filling strips wedged in said spaces, bolts connecting said filling-strips with the exterior shell, and means for feeding the material to be separated into contact with the internal periphery of the cylinder.

5. In a magnetic separator, a rotatable cylinder comprising an exterior shell, a plurality of pole-pieces secured to said shell each comprising a core projecting radially inwardly from the shell and an arcuate head forming part of an interior shell and forming a portion of the internal periphery of the cylinder and inwardly beveled at its longitudinal edges to provide between adjacent 10 heads outward tapering spaces, wedge-shaped filling strips in said spaces and tension means connecting said filling-strips with the exterior shell.

4. In a magnetic separator, a rotatable cylinder comprising an exterior shell, a plurality of pole-pieces secured to said shell each comprising a core projecting radially inwardly from the shell and an arcuate head forming part of an interior shell and forming a portion of the internal periphery of the cylinder and inwardly beveled at its longitudinal edges to provide between adjacent 15 heads outward tapering spaces, wedge-shaped filling strips in said spaces and tension means connecting said filling-strips with the exterior shell.

5. In a magnetic separator, a rotatable cylinder comprising pole-pieces having their inner faces forming a section of the internal periphery of the cylinder, non-magnetic

strips between the pole-pieces, packing interposed between the contiguous surfaces of the strips and the pole-pieces to render the 20 internal periphery of the cylinder watertight, and means for securing the strips and pole-pieces together.

6. In a magnetic separator, a rotatable cylinder comprising an exterior para-magnetic shell, pole-pieces secured to said shell each having a core extending radially inward from the shell and an arcuate head shaped to provide tapering surfaces between the adjacent heads, wedge-shaped filling strips in said spaces, packing interposed between said strips and the contiguous surfaces of the heads, and means for securing said strips in said spaces.
